UNITED STATES PATENT OFFICE.

ROBERT O. VANDERCOOK, OF EVANSTON, ILLINOIS.

INKING DEVICE FOR PRINTING-PRESSES.

1,120,868.

Specification of Letters Patent. Patented Dec. 15, 1914.

Application filed August 1, 1913. Serial No. 782,456.

To all whom it may concern:

Be it known that I, ROBERT O. VANDERCOOK, a citizen of the United States, and a resident of Evanston, in the county of Cook 5 and State of Illinois, have invented certain new and useful Improvements in Inking Devices for Printing-Presses; and I do hereby declare that the following is a full, clear, and exact description thereof, reference being had to the accompanying drawings, and to the letters of reference marked thereon, which form a part of this specification.

This invention relates to improvements in inking devices for printing presses and consists of the matters hereinafter described and more particularly pointed out in the appended claims.

The invention as illustrated herein is shown applied to a hand-operated, proof 20 printing press of a type heretofore invented by me and described in Letters Patent No. 1,042,848 granted me on the 29th day of October, 1912, the same consisting of a horizontal bed for the support of the type, and 25 of a rolling or rocking impression member which is held down to its work by means of the engagement of rollers carried by the impression member with the bottom faces of horizontal tracks made rigid with and extending at each side of the bed. While the 30 improved features of the inking mechanism make its use in connection with such a press of particular advantage, it is not limited to such a press but is capable of application 35 to other presses including power presses as well as to hand-operated presses.

In the drawings:—Figure 1 is a view representing a side elevation of a press of the type described provided with my improved inking mechanism. Fig. 2 is a view representing a transverse vertical section through the same in a plane indicated by line 2—2 of Fig. 3. Fig. 3 is a view representing on an enlarged scale, a top plan 45 view of the press. Fig. 4 is a view representing a longitudinal, vertical central section through the press in a plane indicated by the line 4—4 of Fig. 3. Fig. 5 is a view representing a longitudinal, vertical central 50 section through the inking mechanism on a still larger scale. Fig. 6 is a view representing said inking mechanism in side elevation. Fig. 7 is a view representing a sec-

tion through Fig. 5 in a plane indicated by the line 7—7 thereof. Fig. 8 is a detail 55 view to be more particularly referred to later.

Referring now to that embodiment of my invention illustrated in the drawings, 10 indicates the bed-plate of a printing press 60 of the type described, and 11 a suitable table upon which it is supported.

12 indicates the impression member which comprises a cylindric platen 13 having annular end flanges 14 adapted to roll on suitable horizontal tracks located on each side of the bed-plate and extending longitudinally thereof.

15, 15 indicate gears fixed to said end flanges 14 and adapted for engagement with 70 longitudinally extending rack-bars located adjacent to the aforesaid tracks. The flanges 14 are made rigid with hubs 16, 16, being connected thereto as shown by means of spokes 16^a, and in said hubs are fixed 75 stub-shafts 17, 17, on which are mounted rotative, depending arms 18, 18, each of which carries at its lower end longitudinally spaced rollers 19, 19. Said rollers have rolling engagement with the bottom 80 surfaces of longitudinally extending tracks 20^a, 20^b made rigid with and arranged at each side of the bed-plate 10. The construction thus far is substantially as described in the patent hereinbefore mentioned and forms no part of the present invention.

At each end of the bed-plate there is provided an inking plate 20 which is made rigid with the bed-plate with its top surface 90 in the horizontal plane in which the faces of the type are adapted to lie.

21, 21 indicate two laterally spaced, parallel inking rolls arranged transversely of the bed-plate and supported in a carriage 95 22 adapted to travel longitudinally of the bed-plate. The carriage 22 consists of end plates 23, 23, located at the sides of the bed-plate and connected by rods 23^a, 23^b, extending transversely of the bed-plate and 100 of bearing blocks 24, 24, each supported on one of said end plates. The inking rolls 21, 21, have shafts or studs 21^a extending beyond their ends and bearing in suitable grooves 26^a formed in said bearing blocks. 105 The shafts are confined in said grooves by

means of removable bars 26 each secured to the associated end plate by bolts or screws 27, 27.

The bearing blocks 24 are preferably made vertically adjustable on the end plates 23 in order to adjust the space between the contact surfaces of the inking rolls and the surface of the inking plates and of the type faces to compensate for variations in the 10 diameters of the inking rolls due to changes in atmospheric conditions and wear of the rolls. To this end the bearing blocks have horizontal end extensions 28^a, 28^a, through which bearing screws 28, 28 are threaded 15 and the end plates 23 have horizontal shoulders 23^a, 23^a on which said bearing screws rest. Lock-nuts 29, 30 are placed on each screw, respectively, below and above the end extensions 28^a of the bearing block to 20 lock the same in position when adjusted.

In order to anchor the bearing blocks to the end plates of the carriage, the screws 27, which serve to attach the bars 26 to said blocks are, as shown herein, made long 25 enough to extend into said end plates with which they have threaded engagement. When adjusting the bearing blocks it is necessary to first loosen said screws.

The carriage 22 is provided with devices 30 for engagement with suitable tracks or ways on the bed-plate so that said carriage may be caused to travel over the bed-plate and so that it may be properly held down to its work. Each end plate has longitudinally 35 spaced depending arms 32, 32 carrying horizontal stub-shafts 33, 33, at their lower ends on which are journaled rollers 34, 34. On one side of the bed-plate, that is to say, the left-hand side as viewed in Fig. 2, there is 40 secured a longitudinally extending bar 35 which is let into a suitable recess formed in the bed-plate. Said bar has formed on its upper side along its outer edge, a longitudinally extending row of rack-teeth 36 which 45 are adapted for engagement with one of the gears 15 of the impression member. Extending in a plane adjacent to the row of rack-teeth 36 is a bar 37 fixed in a recess in the upper surface of the bar 35. This bar 50 37 constitutes a bearing rail for one of the annular flanges 14 of the impression member.

38 indicates a second row of rack-teeth formed on the upper side of the bar 35 and 55 extending alongside of the rail 37. On the shafts 21^a of the inking rolls are keyed gears 39, 39, which engage the rack-teeth 38. As the carriage is moved along the bed-plate the engagement of the gears 39 with the 60 rack-teeth 38 imparts a rotary movement to the inking rolls. The teeth of the gears 39 and the rack-teeth 38 are cut to allow for the required vertical adjustment of the inking rolls.

65 On the inner vertical face of the bar 35

is formed a laterally opening channel 39^x having horizontal top-side and bottom-side walls in which the rollers 34 of the adjacent end plate of the ink roll carriage engage, 70 said rollers and channel co-acting to provide an antifriction bearing both for the support of that end of the carriage and also to hold the carriage down to its work.

On the opposite side of the bed-plate there are provided two adjacent longitudinally 75 extending bars 40, 41 let into a suitable recess in said plate, the first of which, 40, has provided on its upper side, gear teeth 40^a for engagement with the gear 15 at the adjacent end of the impression member and 80 the upper face of the other, 41, providing a bearing rail for the adjacent annular flange 40 on the impression member. In the inner vertical face of the latter bar there is provided a channel 41^a which is placed over 85 against the above mentioned channel 39^x and in which are engaged the rollers 34 carried by the adjacent end plate of the inking roll carriage.

On the bed-plate between the inking plates 90 are provided longitudinally extending ribs 42, 42, which act to define the space in which the type or type forms may be placed without interfering with the movement of the carriage. It is apparent that by means of 95 this construction the inking carriage may be easily moved from the inking plate at one end of the bed-plate over the type on the intermediate part of the bed-plate to the inking plate at the opposite end of the bed-plate, the rollers of the carriage traveling 100 in the channels 39^x, 41^a, and the gears 39 on the inking rolls by their engagement with the rack 38 causing the inking rolls to rotate. One of the transverse rods 23^x of the 105 carriage may be grasped to produce this movement and it is apparent that ink spread or placed upon one of the inking plates 20 may be smoothly and evenly applied to the surfaces of the inking rolls, after they have 110 been properly adjusted with reference to said inking plates, as above described, by moving the carriage backward and forward over the same in a familiar manner.

In order to provide for distribution of the 115 ink in a longitudinal direction over the surfaces of the inking roll, I adopt the following: 43, 43 indicate spaced, vertical pins rising from each bearing block 24 of the carriage. On said pins is mounted a vertically 120 movable frame 44 comprising apertured end plates 45, 45, through which the pins extend and transversely extending, spaced connecting rods, 47, 47. 48, 48 indicate parallel 125 spaced, spreading rolls extending parallel to the inking rolls 21 and each adapted for rolling contact with one of said inking rolls. The rolls 48 are journaled in the end plates 45 of the frame 44.

The end plates 45 are provided in a plane 130

midway between the rotative axes of the inking rolls 21, 21, with vertical notches 49, in which are mounted the flat sided ends 50^a of a long screw 50 extending parallel to the inking rolls.

51 indicates a tubular roll which is less in length than the width of the space between the end plates 45, and which is adapted to be brought into contact with both inking rolls. Said tubular roll has an inwardly projecting, radial pin 51^a adapted for engagement with the thread of the screw 50. Thus, when the frame 44 is vertically adjusted so that the tubular roll 51 is in rolling contact with the two inking rolls 21, 21, the rotative movement imparted to said tubular roll by the inking rolls in the movement of the carriage over the bed-plate, will cause the tubular roll to travel endwise from one side of the carriage to the other, thus distributing the ink longitudinally over the surfaces of the inking rolls.

At one end of the screw 50, (the left hand end as shown in Fig. 3,) is provided a cam 52 (see Fig. 8 which is a detail sectional view showing the tubular roll when at that end of the screw,) which has a cam surface 52^a for engagement with the pin 51^a inclined in a direction opposite to the inclination of the screw-threads. When the tubular roll has traveled to that end of the screw, the pin 51^a will strike the cam 52 which will act as a stop to prevent further longitudinal movement of the roll in that direction. When the movement of the carriage is reversed, and the inking rolls and the tubular roll with them are caused to rotate in a reverse direction, the cam surface 52^a guides the pin 51^a back into engagement 40 with the thread of the screw which now produces an endwise movement of the tubular roll back in the direction from which it came. It will be apparent that when the carriage is moved backward and forward over one of the inking plates in applying the ink to the inking rolls that the tubular roll will travel first toward one end of the inking rolls and then back toward the other, thus acting to spread and distribute the ink longitudinally over the surfaces of said rolls. At the same time the small rolls 48 assist in distributing the ink transversely of said rolls.

The frame 44 is movable vertically so that the rolls 51, 48 and 48 carried thereby may be brought into engagement or contact with the inking rolls, as illustrated in Fig. 5, or may be raised into a position where they do not engage said inking rolls, as illustrated in Fig. 6 when the press is idle, to prevent wear. To produce this movement and to support the frame 44 in its upper position, levers 53 are fulcrumed to the bearing blocks 24 of the inking rolls. 65 54 indicate the pins on which said levers are

fulcrumed and 55 a transversely extending bar connecting the ends of said levers and constituting a handle for operating them. The levers are bell-cranks and have arms 56 carrying laterally extending pins 57 which are adapted for engagement with the end plates 45 of the frame 44. Said end plates have centrally located, depending tongues 58 in which are formed cam grooves 59 for engagement with the pins 57. Said cam grooves are so formed that when the levers are in position, such as to hold the frame 44 in its upper position the cam grooves by their engagement with the pins will lock the levers in that position. In order to bring the frame into its lever position, it is necessary first to move the levers so as to slightly raise the frame 44 after which, by reason of the formation of the cam grooves, the further lifting of the operating ends of the levers will permit the frame to descend to its lower position. By depressing the operating ends of the levers a movement of the frame to bring it to its upper position is produced.

The platen 13 of the impression member 12, forms as shown only a part of a cylinder, there being an open space or gap 60 on one side of the impression member. The impression member is placed on the bed in such manner and the bed is of such length that when the impression member is rolled to one end of the bed-plate this gap comes above the carriage of the inking mechanism. Thus the impression member may be 100 rolled to either end of the bed-plate without interfering with the inking member, when the carriage is in its normal position above the inking plate. It may sometimes happen, however, that by carelessness or otherwise, the carriage is left in an intermediate position on the bed-plate. In this position if allowed to stand there, it would be struck by the platen. To prevent any possibility of this occurring I secure to one 110 end plate of the carriage a cam-rod 61.

62 indicates an annular groove located in the vertical plane of the rack-bar 38 which is engaged by the gears 39 on the inking roll arranged to provide for the movement 115 of the impression member without the platen thereof coming into contact with said rack 38. The cam-rod 61, as shown, is arranged in the plane of said groove and is so formed that in case the carriage is left 120 in an intermediate position on the bed-plate in the path of the platen of the impression member and on either side thereof, the cam 61 will be engaged in the groove 62 in said platen and the carriage will be caused to 125 travel toward the end of the bed-plate.

For moving the impression member over the bed-plate one of the arms 18 is provided with an upright radial arm 65 which may be grasped in producing the desired 130

movement. It is apparent that force supplied in a horizontal direction against said arm 65 will cause a rocking or rolling movement of the impression member over the bed-plate. To stop the impression member when it reaches the end of the bed-plate, bumpers 66 are provided at each end and at each side of the bed-plate and the arms 18, 18 carrying the rollers 19 are provided 10 with inwardly extending lugs or shoulders 67 (see Fig. 2) in line with said bumpers.

While in describing one embodiment of my invention I have referred to certain details of mechanical construction and arrangement, not only with respect to the invention itself but also with respect to the press to which it is applied, it is to be understood that the invention is in no way limited thereby either in construction or in 20 its application, except as pointed out in the appended claims.

I claim as my invention:

1. An inking device for printing presses comprising in combination with a type supporting bed one or more inking rollers, an inking plate, a carriage in which said inking roller or rollers are rotatively mounted, means for adjusting said inking roller or rollers in said carriage with reference to the 25 plane of their work, tracks extending at each side of said inking plate and type bed providing laterally opening channels having top and bottom sides, depending arms 30 on said carriage, an antifriction device carried by said carriage and adapted for engagement with the top and bottom sides of said channels, gears on said inking rollers, and a rack extending adjacent to one of said 35 tracks engaged by said gears.
2. An inking device for printing presses comprising in combination with a carriage, inking rollers rotatively mounted in said 40

carriage, spreading rollers of small diameter one for each inking roller, adapted for engagement with said inking rollers, a second 45 spreading roller of larger diameter than said first named spreading rollers, said second named spreading roller being of less length than the length of said inking rollers and being tubular, a screw extending transversely of said carriage on which said second named spreading roller is rotatively mounted, and co-acting devices carried on said screw and said tubular spreading roller acting to limit the movement of said spreading roller when it has reached one side of said carriage and to direct it into proper engagement with said thread when the movement of said carriage is reversed.

3. In combination with a printing press, 60 comprising a bed-plate and a rolling or rocking impression member provided with a cylindric platen, an inking plate at the end of said bed-plate, the platen of said impression member being provided with a gap 65 adapted to lie above said inking plate when the impression member is rocked or rolled to the inking plate end of said bed-plate, a carriage adapted to travel over said inking plate and over said bed-plate, inking rollers 70 carried thereby and a cam device on said carriage and adapted to be struck by the platen of said impression member and to drive said carriage toward said inking plate when said carriage is left in the path of said 75 impression member.

In testimony, that I claim the foregoing as my invention I affix my signature in the presence of two witnesses, this 29th day of July A. D. 1913.
